CLAIM

The ornamental design for a telephone stand, substantially as shown and described.

DESCRIPTION

FIG. 1 is a perspective view showing our new design for a telephone stand intended for use on a vertical surface;

FIG. 2 is a front view taken perpendicular to the face of the telephone stand;

FIG. 3 is a side elevation thereof;

FIG. 4 is a top plan view thereof;

FIG. 5 is a bottom plan view thereof;

FIG. 6 is a front view taken perpendicular to the face of a second embodiment of the telephone stand illustrated in FIGS. 1 through 5;

FIG. 7 is a top plan view thereof;

FIG. 8 is a bottom plan view thereof;

FIG. 9 is a front view taken perpendicular to the face of a third embodiment of the telephone stand illustrated in FIGS. 1 through 5;

FIG. 10 is a top plan view thereof;

FIG. 11 is a bottom plan view thereof;

FIG. 12 is a front view taken perpendicular to the face of a fourth embodiment of the telephone stand illustrated in FIGS. 1 through 5;

FIG. 13 is a top plan view thereof;

FIG. 14 is a bottom plan view thereof;

FIG. 15 is a front view taken perpendicular to the face of a fifth embodiment of the telephone stand illustrated in FIGS. 1 through 5;

FIG. 16 is a top plan view thereof;

FIG. 17 is a bottom plan view thereof;

FIG. 18 is a front view taken perpendicular to the face of a sixth embodiment of the telephone stand illustrated in FIGS. 1 through 5;

FIG. 19 is a top plan view thereof; and

FIG. 20 is a bottom plan view thereof.
